GRINDING MACHINE

Walter Mark Bura, Washington, D. C., assignor
to Norton Company, Worcester, Mass., a corporation of Massachusetts

Application June 21, 1946, Serial No. 678,195

5 Claims. (Cl. 51—56)

1

The invention relates to grinding machines and with regard to its more specific features to a grinder for grinding cutting tools, bits, milling cutters and the like, especially those having tips of cemented carbide.

One object of the invention is to provide such a grinder which will shape such tools, bits, milling cutters and the like to form desired angles of clearance without the use of a sliding tool holder or the like. Another object of the invention is to provide a grinder of the type indicated which will shape such tools, etc. without the use of any patterns, blocks, cams or the like to control the generated shape. Another object is to provide relief in the direction of the feed (as in a lathe) of the tool, of constant or nearly constant angularity while the tool is rigidly clamped to the table of the machine.

Another object of the invention is to provide a grinder for the generation of relief or clearance angles in which more reliance is placed upon the brains of the operator and less upon the skill of his fingers.

Another object of the invention is to provide a universal grinder that can be set to shape many and various curved surfaces and that has means to provide a feeding component for grinding by increased increments without upsetting the generation or changing the shape of such curved surface.

Another object of the invention is to provide a grinder having some of the above characteristics which may also be used to produce ordinary right circular cylinders, right circular cones or other common shapes. Another object of the invention is to provide a grinder with one or more of the above characteristics which will also function as a surface grinder to grind a plane surface.

Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings illustrating one of many possible embodiments of the mechanical features of this invention,

Figure 1 is an elevation of a grinding machine constructed in accordance with the invention;

Figure 2 is likewise an elevation of the machine, looking from the left in Figure 1;

Figure 3 is a plan view of the machine;

Figure 4 is a sectional view, taken along the line 4—4 of Figure 2;

Figure 5 is a sectional view taken along the line 5—5 of Figure 1;

Figure 6 is a sectional view taken along the line 6—6 of Figure 4;

2

Figure 7 is a sectional view taken along the line 7—7 of Figure 3.

Referring to Figure 1, the machine has a relatively low and hollow base 10 joined to a relatively high and hollow base 11 which in plan view is of narrow rectangular shape. The base 10, which is approximately square, supports a series of slides and a revolving table, while the base 11 supports a movable carriage 12. The slides 10 and the rotatable table support the work piece, while the carriage 12 supports a grinding wheel 13.

Referring now to Figure 4, the base 10 has a flat way 14 and a V-way 15 on which are located mating parts 16 and 17 of a slide 20. Depending from a table 21 is a large trunnion 22 which is journaled in radial ball bearings 23 and 24. The outer race of upper ball bearing 23 fits with a press fit in a hollow cylindrical portion 25 integral with and depending from the slide 20. The outer race of lower ball bearing 24 fits in a cap 26 which fits in and closes the lower end of the hollow cylindrical portion 25, whereby the ball bearings 23 and 24 are protected from any dust in the base 10. Referring for a moment to Figure 1, the cap 26 may readily be reached through a door 27 mounted on hinges 28 on the front of the base 10.

Thus the table 21 is journaled in the slide 20 for angular adjustment thereon, or for rotation or oscillation as may be desired. The weight of the table 21 and the elements supported by it are taken by a third ball bearing 30 which is a thrust bearing, the lower race of which rests 35 in a circular groove 31 formed in an annular ledge 32 integral with the hollow cylindrical portion 25 and just above it, and the upper race of which supports the table 21 and is located by an annular shoulder 33 on the trunnion 22. The three ball bearings, 23, 24 and 30 are coaxial and the construction described journals the table 21 for angular movement with very little effort about a fixed axis with substantially no play or lost motion.

The table 21 has a flat way 35 and a V-way 36 upon which rest the mating parts 37 and 38 of a slide 40. Referring now to Figure 6, the slide 40 has a flat way 41 and a V-way 42 upon which rest the mating parts 43 and 44 of a table 45. The table 45 is a slide because it is movable on the ways 41 and 42; it is also a table to hold a work piece or a fixture for holding a work piece, as may be desired. To that end the table 45 has a T-slot 46 in the upper surface 47 thereof which is otherwise flat and horizontal. Likewise in one side surface 50, which is otherwise flat and vertical there is a T-slot 51. By means of the T-slot 46 any tool holder or other fixture, and certain work pieces may be rigidly clamped to the table 45.

The T-slot 51 adjustably holds a dog 52 the purpose of which will be later explained.

Referring now to Figures 1 and 2 on the front of the machine is a handwheel 55. This handwheel 55 is secured to the front end of a screw shaft 56 which is shown in cross section in Figure 4. As shown in Figure 2 a collar 57 is secured to the screw shaft 56, and the collar 57 abuts a thrust bearing 58 through which the screw shaft extends and in which it is journalled. The bearing 58 is attached to the front of a box 59 fastened to and extending forwardly from the front of the base 10. In the box 59 is a collar, not shown abutting the other side of the bearing 58. Thus the screw shaft 56 is held against axial movement. It passes through a pair of nuts 60, only one of which is shown in Figure 4, which nuts are formed integral with the cylindrical portion 25. The nuts 60 are fairly thin and can be flexed toward each other by a bolt 61 in order to remove play between the nuts and the screw shaft 56. By turning the handwheel 55 the slide 20 can be moved, and also accurately adjusted.

The slide 40 is similarly adjustable and movable upon the table 21 and likewise the table 45 is adjustable and movable upon the slide 40. As shown in Figures 1, 2, 3, and 4 there is a handwheel 65 on one end of the slide 40 which is fastened to a screw shaft 66 which passes through a nut 67 secured to the table 21. The screw shaft 66 is journalled in a thrust bearing, including a collar 68 fastened to the shaft 66 and a part 69 of the slide 40.

Referring now to Figures 1, 3, and 4 there are a pair of hand wheels 70 secured to the ends of a screw shaft 71 which is journalled in depending portions 72 of the table 45. Collars 73 and 74 hold screw shaft 71 against axial movement relative to the table 45. Screw shaft 71 passes through a nut 75 which extends upwardly from and is formed integrally with the slide 40.

It is important to be able to lock the revolving table 21 in any desired angular position. To this end, as shown in Figure 4, I provide a lever 76 journalled on a stud 77, the lever 76 having a partial gear 78 formed thereon which meshes with a gear 79 which is secured to a shaft 80 upon which is a cam 81. When the lever 76 is turned, cam 81 is rotated and wedges the table 21.

It is also desirable to be able to set the table 21 at a given angle without the use of instruments. To that end on the conical surface 84 of the table 21 are a number of rubberlines 85 and upon the conical surface 86 of the slide 20 are scale marks. Further, to facilitate the setting of the table 21, I provide a T-slot 88 for adjustable securing a number of dogs 89 which have arms 90, pivotally mounted at 91. These arms 90, when lowered, engage the upper end of a stop 92 extending upwardly from the cylindrical portion 93 of the slide 20. This cylindrical portion 93 of slide 20 merges into the conical portion 86. Only one dog 89, arm 90 and stop 92 is shown in the drawings, but several dogs 89 and arms 90 may be provided and, if desired, more than one stop 92. The dogs 89 are movably mounted on T-bolts 94 which extend into the T-slot 88.

Referring now to Figure 3, means are provided accurately to adjust the position of the slide 20. A bracket 96 is secured to the base 10 and has an open slideway 97. To the bracket 96 is secured a dial micrometer gauge 98. Blocks 99 may be placed in the slideway 97, these blocks being of designated length to very close toler-

ances. A dog 100 located in a T-slot, 101, Figure 1, in the slide 20 engages either a block 99 or the needle of the dial micrometer gauge 98 and thus the slide 20 may be adjusted to various exact positions and readjusted by small increments.

Similarly the dog 52 in the T-slot 51 of the table 45 may engage a block 102 in an open slideway 103 of a bracket 104 attached to the slide 40, or it may engage the needle of a dial micrometer gauge 105, for the accurate adjustment of the table 45.

Referring now to Figures 1 and 5, the high hollow base 11 has a dovetail portion 110 on the top of which is a flat slideway 111. Opposite this dovetail portion 110 is another dovetail portion 112 likewise having a flat slideway 113 on the top thereof. The carriage 12 is a hollow rectangle in cross section and the lower wall 114 thereof has a smooth plane surface on the bottom which rests upon the slideways 111 and 113. Extending downwardly from the ends of the lower wall 114 are outer dovetail portions 115 and 116 which mate with the dovetail portions 110 and 112. Gibs 117 adjusted by bolts 118 complete the slideway for the carriage 12 which can thus move freely on the base 11 in a straight horizontal line but is firmly held from any side motion. The carriage 12 may also be locked rigidly in position by means of a screw 120 extending through a stationary nut 121 extending downwardly from the top wall 122 of the carriage 12, as the screw 120 abuts a lever 123 which is mounted on a pin 124, and the lower end of the lever engages a gib 117. The pin 124 is held by ears 125 extending from the side wall 125 and the bottom wall 114.

Referring now to Figures 5 and 7, bolted to the lower wall 114 by means of bolts 128 is a casting 129. This casting 129 holds a cylinder 130 in which is a piston 131 connected by hollow piston rods 132 to brackets 133 which are hollow and admit and exhaust fluid to and from the hollow rods 132. The brackets 133 are mounted on the base 11 and have the double function of holding the rods 132 and transmitting fluid. The carriage 12 can be automatically reciprocated by means of the piston and cylinder unit 131 and 130 which can be controlled by a reversing lever 134 (Figure 1) pivoted at 135 which is engaged by reversing dogs 136 adjustably mounted in a T-slot 137 on the side of the carriage 12. The speed of travel of the carriage 12 can be adjusted by means of a knob 138 which is turned to change the setting of a valve, and the carriage can be started and stopped by means of a lever 139 which pulls the knob 138 out or pushes it in. The various valves and the hydraulic diagram are not herein disclosed because such are now well known in the art. I prefer to use the Norton hydraulic system as disclosed, for example, in U. S. Patent No. 2,071,677, which is hereby incorporated by reference.

Sometimes it is desirable to move the carriage 12 by hand. Referring now to Figure 5, the dovetails 110 and 112 are connected by casting portion 140 which is a U-shaped in cross section and in one side wall of which are bores for a shaft 145 and a stud 146. On the shaft 145 are spur gears 147 and 148, the former meshing with a rack 150 which is fastened to the casting 129. Gear 148 meshes with a gear 151 on the stud 146, and gear 151 meshes with a gear 152. The gear 152 has a clutch portion 153 which can be engaged by a clutch portion 154 on the end 70 of a hub 155 of a handwheel 156. The hub 155

is slidably and rotatably mounted in a bore 157 in the front wall of the high hollow base 11. Through the hub 155 and through the gear 152 and into a bore 158 in the casting portion 140 extends a shaft 159 which abuts a spring 160. When the handwheel 156 is pushed, the clutches 153 and 154 engage, and then by turning the handwheel 156 the carriage 12 can be traversed on the base 11. The spring 160 automatically disengages the clutches 153 and 154 when the handwheel 156 is released. A pin 161 extending into a groove 162 in the hub 155 prevents the handwheel 156 and shaft 159 from being accidentally removed from the machine.

Referring now to Figures 1, 3, and 7 on the front of the carriage 12 are a pair of dovetail portions 165, 165 forming a slide way upon which is mounted a vertically movable slide 166 having co-operating dovetail portions 167, 167. Gibs 168 and bolts 169 are provided for the joint purpose of eliminating lost motion and locking the slide 166 in a desired vertical position.

On the side of the carriage 12 is a handwheel 170 which is secured to a shaft 171 which is suitably journaled in the carriage 12. The shaft 171 extends into a hollow box portion 172 formed in the forward part of the carriage 12. This box portion 172 includes a separate casting 173 in which are formed upper portions of the dovetail portions 165. This separate casting 173 is provided for purposes of assembly. The box portion 172 on its lower side supports a ball thrust bearing 175. The casting 173 receives the thrust of a ball thrust bearing 176. These bearings 175 and 176 support a sleeve 177 having formed in the center thereof a worm wheel 178. With this worm wheel meshes a worm 179 which is keyed to the shaft 171.

The sleeve 177 is internally threaded and receives a screw shaft 180, the top of which is fastened by means of a nut 181 and washers 182 to an overhanging portion 183 of the slide 166. It will thus be seen that the slide 166 may be raised or lowered by turning the handwheel 170 and it may be locked in position by tightening the bolts 169.

Referring now to Figures 1, 2, 3 and 7, on the front of the slide 166 is an integral hollow trunnion 185 (see especially Figure 2) journaled a split bearing 186 of a wheel head support 187. A hand lever 188 is fastened to a vertical shaft 189 which extends through integral bosses 190 and 191 formed on the split bearing 186 on either side of the split. The shaft 189 is free in the boss 190 but in screw threaded engagement with the boss 191. Therefore the bearing 186 may be tightened upon the trunnion 185 to lock the parts together or may be loosened to adjust the wheel head support 187 angularly about a horizontal axis, by moving the lever 188. A rubber line 192 is provided on the bearing 186 and scale markings 193 are provided on the trunnion 185 in order to adjust the wheel head support 187 to known angles.

The wheel head support 187 extends away from the trunnion 185 and terminates in a hollow bearing 195 the transverse plane of which is practically tangent to the trunnion 185. Furthermore, when the zero mark of the scale 193 is on the rubber line 192 this transverse plane is horizontal and the axis of the bearing 195 is vertical. A trunnion 196 of a wheel head 197 fits in the hollow bearing 195. The wheel head 197 supports a motor 198 which drives a shaft 199 journaled in a bearing 200 in the wheel head 197. The

grinding wheel 13, which may be a cup wheel as shown, or may be a peripheral wheel or of any other shape, is fastened to the shaft 199.

The trunnion 196 is held in the bearing 195 by means of a bolt 202 which extends through a boss 203 formed in the wheel head support 187 and into a threaded boss 204 in the center of the trunnion 196. The bolt 202 may be loosened to adjust the wheel head 197 angularly, and tightened to secure the adjustment. It will be noted that there is room to swing the wheel head 197 through a full circle in some positions of the wheel head support 187. The former has rubber lines 205, and the wheel head support 187 has scale markings 206 in order accurately to determine the angle of adjustment of the wheel head 197. When the zero of the scale markings 206 is on one of the rubber lines 205, the axis of the wheel 13 is perpendicular to the slideway 111, 113.

In order to grind a single point tool such as a lathe tool which will have relief or clearance angles in the direction of feed of the tool into the work it is to cut which are of nearly constant angularity, I provide a tool or work holder (not shown) which may be rigidly secured in the T slot 46 in the surface 47 of the work table 45. Such a work holder will be capable of holding the tool to be ground in any angular position. I place the tool in the tool holder and position it so that the shank of the tool is normal to the direction of feed of table 45. In order to grind the side under the side cutting edge to the required relief angle, that is, the side longitudinal 35 of the shank of the tool, I index the wheel 13 to zero by moving the wheel head 197 about its vertical axis until the rubber line 205 comes opposite the zero mark of the scale markings 206. In this position the axis of the wheel will lie in a vertical plane which is parallel to the direction of infeed of the lowest table 20. I then tilt the wheel 13 to the angle to which I wish to grind the relief under the side cutting edge of the tool by moving the wheel head 187 about the horizontal trunnion 185 until the rubber line 192 comes opposite the angle of tilt I desire on the scale 193. The face of the wheel 13 will then lie in the required angle from the vertical. To obtain the desired angle of relief under the front cutting edge of the tool to be ground, I tilt the tool from the horizontal through an angle which is the difference between the side and front relief angles required by adjusting the holder. To form a radius at the corner of the tool where the cutting edges meet, I back away the lower cross slide 20 from the wheel face by means of wheel 55, until the center of the table 21 is away from the wheel face by the amount of the required radius, as indicated by the dial micrometer gage 98. The radius will also depend upon the height of the tool edge with respect to the wheel face because the wheel has been tilted. This has been taken into account when the micrometer gage 98 is indexed. I then set the revolving table stops 89 so that the table 21 will swing the tool through an angle 55 at one limit of which its side cutting edge is presented to the face of the wheel 13 and at the other limit of which its front cutting edge will be presented to the face of the wheel 13. In setting the limit stops 89 I determine the limits of the angle of swing of table 21 to adjust the stops 89 by bringing the rubber line 85 opposite the proper readings on the scale 86. I feed the tool longitudinally into the wheel to present the front cutting edge by advancing the table 40 with the wheel 65,

and I feed the side cutting edge in by advancing the cross slide 45 with wheel 70 toward the wheel 13 when the side cutting edge is turned toward the wheel face. To grind the radius where the cutting edges meet I revolve the table 21 between the stops 89. The amount of stock to be removed depends upon the amount I feed the tool into the wheel 13 by the tables 40 and 45 or the resultant of these motions. No matter how much I feed the tool into the wheel 13 by advancing tables 40 or 45, I will grind the same radius and the same side and front cutting edge relief angles for which I set the machine up. Feeding in the tool by moving the tables 40 and 45 simply causes more stock to be removed, but the resulting shape of the cutting edges of the tool will remain the same. It will be seen that by rotating the tool upon the table 21 against the face of the wheel 13 as I grind the radius, the predetermined relief angle under the side cutting edge of the tool automatically changes to the angularity I have set for the relief under the front cutting edge of the tool.

To grind a multiple toothed tool such as a peripheral and face mill to obtain constant angularity of relief in direction of feed (of the tool toward the work it cuts) I provide a work holder which is capable of holding the shank of such a cutter tool to the wheel face at any angle, and I clamp it to the work table 45 by means of the T slot 46. I place the tool therein, so that its shank lies horizontally and in a vertical plane which is at right angles to the direction of feed of the work table 45. I index the wheel 13 about its vertical turning axis to zero as before, so that the wheel spindle lies in a vertical plane which is parallel to the tableway 20, and I tilt it about its horizontal axis to the angle of relief (from the vertical) I desire the face of the tool to have. I then rotate the table 21 to position the face cutting edge against the wheel by advancing table 40 by means of wheel 65. I limit the rotation of table 21 at this position by setting a limit stop 89. I then rotate the table 21 to present the peripheral cutting edge of the tool to the wheel face by advancing table 45 with wheel 70 and I limit rotation of table 21 to this position by setting another limit stop 89, so that the table 21 can now rotate between these two angle limits to grind the face, the radius and the peripheral side of the tool in one pass. In order to further support the tool while it is being ground a tooth rest (not shown) integral with the wheel head is provided to support the particular tooth being ground from beneath at the point of grind. To grind the angle of relief desired on the peripheral face, the tooth rest is adjusted up or down (as the set up indicates) the tool is rotated on its axis through an angle which is equal to the difference between the two cutting edge relief angles I desire. I back the table 21 away from the face of the wheel 13 on its slide 20 by means of feed wheel 55 so that its center lies away from the wheel face an amount equal to the radius I want at the corner between the face and peripheral cutting edges of the tool. This will produce the required angle of relief under the peripheral cutting edge. For example, on a cutter tooth requiring 3° relief in the face cutting edge and 7° on the peripheral cutting edge, the wheel would be tilted 3° from the vertical and the tooth rest lowered through an angle of 4°. The change from one angle to the other is accomplished automatically as the table 21 is rotated between the limit stops 89 as set to grind the radius, which results in the shape

of a right truncated cone on the corner where the radius is ground.

These two illustrations of the machine operation describe functions for which this machine is particularly well adapted. In surface grinding the wheel 13 will automatically traverse the work as it moves on its hydraulically driven carriage 12, while set at any angle of tilt desired. Infeed is controlled by the movable tables as described above, and depth of cut by the wheel 170 to lower the wheel vertically. The seven motions in the machine to control movement of the wheel and the work (exclusive of work positioning by means of a tool holder not shown) relative to each other together with micrometer gages allow controlled grinding of an infinite number of shapes without the use of templates, patterns, cams or the like.

It will thus be seen that there has been provided by this invention apparatus in which the various objects hereinabove set forth together with many thoroughly practical advantages are successfully achieved.

As many possible embodiments may be made of the above invention and as many changes might be made in the embodiment above set forth, it is to be understood that all matter hereinbefore set forth (or shown in the accompanying drawings), is to be interpreted as illustrative and not in a limiting sense.

I claim:

1. In a grinding machine, a base, a slide directly upon said base, a rotatable table directly upon said slide, a second slide directly upon said rotatable table, a third slide directly upon said second slide movable at an angle to said second slide, a second base connected to said first base and extending above it, a horizontally sliding carriage on said second base, a vertically movable slide on said sliding carriage, an angularly adjustable wheel head support on said vertically movable slide adjustable about a horizontal axis, and a wheel head carried by said wheel head support and angularly adjustable about an axis normal to the axis of said wheel head support, the wheel head being over the table whereby a grinding wheel mounted thereon may operate upon a work piece held by said third slide.

2. In a grinding machine, a base, a slide movable on said base, a hollow cylindrical portion extending downward from said slide into said base, a table, a downwardly extending trunnion under said table, means for journaling said trunnion in said hollow cylindrical portion whereby said trunnion is angularly movable, additional thrust bearing means between said slide and said table for supporting said table from said slide, a slide carried by said table which is movable in a plane perpendicular to the axis of said trunnion, and a further slide on the slide carried by said table, said further slide being movable in a plane parallel to but in a direction at an angle to the slide carried by the table.

3. In a grinding machine, a base having a low portion and a high portion, a horizontally sliding carriage mounted upon said high portion, a vertically movable slide carried by said carriage, a wheel head support journalled on a horizontal axis in said slide, a wheel head journalled in said support on an axis normal to said horizontal axis, a slide mounted directly upon the low portion of said base, an angularly adjustable table mounted directly on said slide which is upon the low portion of said base, and a pair of slides one above the other on said table, said slides on said table

being movable at an angle to each other but in planes parallel to each other, and the wheel head being over said table, whereby a grinding wheel carried by the wheel head can operate on a work piece held by the top slide of the pair of slides one above the other on said table.

4. In a grinding machine as claimed in claim 3, the combination with the parts and features therein specified, of means for feeding each of said slides.

5. In a grinding machine as claimed in claim 3, the combination with the parts and features therein specified, of means for accurately locating said table and means for accurately locating one of said slides.
